ADJUSTABLE SUPPORT FOR HEADRESTS

Filed July 27, 1929

UNITED STATES PATENT OFFICE

CHARLES W. FISCHER, OF CHICAGO, ILLINOIS, ASSIGNOR TO THEO. A. KOCHS COMPANY, OF CHICAGO, ILLINOIS, A CORPORATION OF ILLINOIS

ADJUSTABLE SUPPORT FOR HEADRESTS

Application filed July 27, 1929. Serial No. 381,422.

This invention relates to adjustable supports for head rests, and its principal object is the provision of simple means for supporting the head rest of a barber's chair concealed from view when not in use. It is well known that the head rest of a barber's chair is frequently detached from the chair and ordinarily is placed on the floor or elsewhere, giving an untidy appearance to the surroundings. In accordance with the present invention, the head rest support when detached from the chair, is temporarily supported below the seat of the chair where it is hidden from view.

Another object of the invention is to provide an adjustable support for head rests which may be easily attached to a member of a barber's chair without making any changes whatsoever in the construction thereof. Another object is to provide a support for the head rest which may be secured in place on the underside of the chair rest without interfering with any of the chair operating mechanism.

With these and other objects and advantages in view, this invention consists in the several novel features hereinafter fully set forth and claimed.

The invention is clearly illustrated in the drawings accompanying this specification in which—

Figure 1 is a side elevation of the seat portion of a barber's chair equipped with an adjustable head rest support embodying a simple form of the present invention;

Fig. 2 is a view, partly in plan and partly in horizontal section, of the parts seen in Fig. 1, the line of section being indicated at 2—2 in Fig. 1;

Fig. 3 is a detail vertical cross section taken on the line 3—3 of Fig. 1; and

Fig. 4 is a detail vertical cross section taken on the line 4—4 of Fig. 2.

Referring to said drawings, which shows the invention applied to a barber's chair of ordinary and well known construction, the reference character 5 designates the seat portion of the chair which is usually provided with a metal flanged frame 6 from which rise the arms 7 and the chair back 8. The seat

portion is supported by a cylindrical member 9 and is provided with means for raising and lowering the seat, as is customary, which means are controlled by a lever 10 disposed at one side of the chair and mounted upon a shaft 11 which extends horizontally below the frame 6 from the lever 10 to the pump mechanism of the seat raising and lowering device. The upper end of the cylindrical member 9 is provided with a horizontally extending flange 12 to which the frame 6 is secured by a spider 13 bolted thereto by bolts and nuts 14, 15. The flange 6^a of the frame 6 projects down from the margin of the frame and covers the connection between the cylindrical member 9 and the seat. As is customary, the chair is provided with a head rest 16 of conventional form, which has the usual slide 17 that is adjustably supported in the chair back 8. The parts thus far described are of standard construction and require no further description as far as this specification is concerned.

The head rest support which forms the subject matter of this specification, and which is employed to hold the head rest when not in use, will now be described. Bolted to the under side of the flange 12 by one of the bolts and nuts 14, 15 is a bracket 18, here shown as formed of a piece of flat bar metal, having a horizontal arm 18^a formed with an aperture 18^b for receiving the bolt 14. The horizontal arm has a downwardly extending upright portion 18^c bent at its lower end to form a horizontal arm 18^d spaced below the horizontal arm 18^a far enough to extend below the shaft 11 of the raising and lowering mechanism. In Fig. 2 it will be seen that the bracket 18 extends from the bolt 14 in an oblique direction, whereby the terminal end of the horizontal portion 18^d may be located adjacent the shaft 11 between the cylindrical member 12 and the flange 6^a of the frame 6.

Swiveled on the arm 18^a of the bracket 18 is a head rest supporting member 19 which receives the slide 17 of the head rest. The head rest supporting member is preferably composed of a channel shaped member 20 of light gauge sheet metal reinforced by a bar 21 secured thereto by screws and nuts 22, 23.

The upper wall of the member 20 may be bent upwardly slightly at its receiving end to facilitate the insertion of the head rest slide. The channel member is formed with inturned flanges 20^a.

- 5 5. The swivel connection between the head rest supporting member 19 and the bracket 18 may comprise a screw 24 which extends through the reinforcing bar 21 and through 10 the horizontal arm 18^a of the bracket 18, a wing nut 25 threaded upon the screw 24 and washers 26 and 27 interposed between the wing nut and arm 18^a. The washer 27 is preferably in the form of a split spring washer. 15 If desired, thin metal disks 28 may be interposed between the arm 18^a and the washer 26 and reinforcement bar 21.

When the device is in use supporting a head rest, it occupies an oblique position, as is illustrated in full lines in Fig. 2, wherein the head rest is concealed below the frame 6 of the chair seat. Desiring to use the head rest, the attendant swings the head rest 16 and therewith the supporting member 19 of 20 the device into the position indicated in dotted lines in Fig. 2, and withdraws the head rest slide 17 from the supporting member 19. In this position, the supporting member remains until it is again used to support the 25 head rest.

When the head rest is not used in connection with the work being performed by the attendant, it is detached from the chair back, the slide 17 inserted into the channel member 20 of the supporting member 19, and swung back into the position shown in full lines in Fig. 2, where it is concealed from view. It is to be observed that the device above described forms a convenient support 30 for holding the head rest when detached from the chair, and that no effort is required to place the head rest on the support and move it underneath the chair seat, or to remove it from the support, and that when 35 supported underneath the chair seat, the head rest is not only concealed from view, but is kept off the floor, and, consequently, is stored under more sanitary conditions.

I claim:

- 50 1. In an adjustable support for head rests, the combination with a bracket, and means for supporting the same on the under side of a chair seat, said bracket having a downwardly projecting portion terminating in a 55 horizontally projecting arm, of a channel shaped supporting member adapted to receive a head rest slide, and a swivel connection between said horizontal arm of the bracket and said supporting member.
- 55 2. In an adjustable support for head rests, the combination with a bracket having one arm adapted to be secured to a supporting member of a chair underneath the seat portion thereof, said bracket having also a horizontally 60 extending arm spaced below the

first mentioned arm, of a horizontally movable channel shaped supporting member adapted to receive a head rest slide, and a swivel connection between said second mentioned arm of the bracket and the supporting 70 member.

3. In an adjustable support for head rests of barbers' chairs having a seat portion and a shaft for seat raising and lowering mechanism, the combination with a bracket, and 75 means for securing the same to the under side of the seat portion of the chair, of a channel shaped horizontally extending supporting member adapted for the reception of a head rest slide, and a swivel connection between 80 said bracket and said supporting member, said supporting member being arranged to underlie said shaft and movable to a position under the seat portion in which the head rest is concealed from view. 85

4. In an adjustable support for head rests of barbers' chairs having a seat portion and a flanged supporting member bolted thereto, the combination with a bracket having an arm bolted to the flange of the supporting 90 member and having another arm disposed below the first mentioned arm, of a horizontally extending channel shaped supporting member adapted to receive a head rest slide, and a swivel connection between the second 95 mentioned arm of the bracket and the supporting member, said supporting member and therewith the head rest being capable of movement underneath the chair seat whereby the head rest is concealed from view. 100

5. In an adjustable support for head rests of barbers' chairs having a flanged support, a chair seat bolted to the flange of the support and a horizontal shaft for raising and lowering mechanism, said shaft being disposed below the seat and flange, the combination with a bracket bolted to the flange of said support and having a horizontally extending arm located below said shaft, of a horizontally extending channel shaped 105 member adapted for the reception of a head rest slide, and a swivel connection between said arm of the bracket and the supporting member, said supporting member being located below said shaft and movable from a 110 receiving position for the head rest to one in which the head rest is located wholly below the seat and concealed from view.

6. In an adjustable support for head rests, the combination with a bracket having oppositely disposed upper and lower arms, one of which is arranged to be attached to the under side of a chair seat, and a horizontally extending channel shaped supporting member adapted for the reception of a head rest 115 slide swiveled to the lower arm of said bracket on a vertical axis whereby it may be swung in a horizontal plane underneath the chair seat.

7. In combination with a barber chair seat 120

and its pedestal, of a head rest support pivotally mounted to one side of said pedestal and in spaced relation with the underside of the chair seat, said head rest support having a receiving end adapted to normally occupy a position adjacent one edge of the chair seat and swingable about the pivot to a position adjacent the pedestal, whereby a head rest may be placed in said support from one side of the chair seat and swung to concealed position beneath the seat.

In witness whereof, I have hereunto set my hand this 23rd day of July, 1929.

CHARLES W. FISCHER.
